ELECTRIC SWITCH

Carl G. Groes, Mount Vernon, N. Y., assignor, by
mesne assignments, to American Machine and
Metals, Inc., New York, N. Y., a corporation of
Delaware

Application October 15, 1935, Serial No. 45,017

2 Claims. (Cl. 200—6)

The present invention relates to a novel and improved electrical switch.

Objects and advantages of the invention will be set forth in part hereinafter and in part will be obvious herefrom, or may be learned by practice with the invention, the same being realized and attained by means of the instrumentalities and combinations pointed out in the appended claims.

0 The invention consists in the novel parts, construction, arrangements, combinations and improvements herein shown and described.

The accompanying drawing, referred to herein and constituting a part hereof, illustrates one embodiment of the invention, and together with the description, serves to explain the principles of the invention.

Of the drawing:

Figure 1 is a plan view, with certain parts broken away, of an illustrative embodiment of the present invention;

Figure 2 is a section taken on the line 2—2 of Figure 1; and,

Figure 3 is a fragmentary detailed section taken on the line 3—3 of Figure 2.

The present invention has for its object the provision of a novel and improved electrical switch adapted to carry relatively heavy currents at commercial voltages, and to control the supply of current to a plurality of branch circuits. A further object is the provision of a simple, reliable and relatively inexpensive, multiple contact switch which is quick and positive in its opening of its contacts.

35 An illustrative switch of the present invention comprises a plurality of quick-acting, toggle-mounted contacts arranged in arcuate relation and cooperating with an arcuate series of stationary, interconnected contacts, the two series of 40 contacts being concentric with each other and with a rotatable toggle-actuating member which can be moved to individually control the position of the several toggle-mounted contacts.

It will be understood that the foregoing general description and the following detailed description as well, are exemplary and explanatory of the invention but are not restrictive thereof.

Referring now in detail to the drawing showing an illustrative embodiment of the present invention, there is provided a base member 10 of insulating material on which are mounted in arcuate relation a plurality of movable contacts 11 supported on toggles adapted to be moved into and out of contact with a similar number of stationary contacts 12 which are arranged arcuately

and concentrically with the contacts 11. A second insulating member 14 is spaced from the member 10 and held in fixed relation thereto by means of the pillars 15, with the toggles, and contacts between the members 10 and 14, and 5 the insulating member 14 carries a shaft 16 to which is fastened a rotatable cam 17 adapted to contact with the toggles and thereby move the contacts 11.

The toggles for supporting and moving the contacts 11 each comprise, more in detail, a U-shaped bracket 20 secured in a recess 21 formed in the member 10 by means of a terminal screw 22 and toggle arms 23 and 24 are pivotally mounted on bracket 20 by means of a pivot pin 25. At a 15 distance from the pivot, arm 23 is formed with an outwardly extending ear 26, while arm 24 is similarly provided with a pair of inwardly extending ears 27. Ears 27 are apertured to receive the ends of a C-shaped wire 28, to the center of which 20 is attached one end of a spring 30 having its other end attached to the ear 26. The points of their respective ears to which the spring 30 and wire 28 are attached are so positioned that in the open position of the switch the ears and these 25 points overlap, while in the circuit closing position these points are positioned apart from each other. At its upper end arm 23 carries the movable contact 11, while the upper end of the other arm 24 is apertured to receive one end of the 30 switch-opening spring 31. The switch opening springs 31 are all connected to a spider 32 surrounding the shaft 16 and journal 16'.

For limiting the throw of the toggle wire 28, and also for making a positive connection between the arm 23 and the terminal screw 22, laterally extending ears 33 extend from the sides of arm 23 to the end of which and terminal screws are connected the flexible conductors 34. Ears 33 are notched, as at 35 to receive and limit the 40 movement of the wire 28.

The stationary contacts 12 are mounted on a cylindrical cup 37 of conducting material which is secured to the member 10 by means of a terminal screw 38 and is held against rotation by 45 means of the studs 39 projecting from member 10 through corresponding apertures in the end wall of cup 37. The stationary contacts 12 are so positioned relatively to each other and to the movable contacts 11 that they contact with their 50 respective contacts 11 when the corresponding toggles are in circuit closing position.

For selectively and individually moving the toggle mounted contacts 11, a camming member 17 is mounted between the plates 10 and 14 and 55

may be turned by means of shaft 16 and knob 41. The outer edge of cam 17 is preferably arcuate and is adapted to be moved into operative contact with the rounded knobs 42 mounted on the arms 24. As shown, cam 17 contacts with only a single knob 42 at a time and selectively and individually operates the switches. For definitely positioning the cam 17 and holding it lightly against accidental movement, cam 17 is recessed 10 as at 43 to receive a ball 45 which is pressed upwardly and into one of the depressions 46 by means of spring 47, each depression corresponding to one switching position.

Figure 2 of the drawing shows the two positions of the switch. At the left, the switch has 15 been closed by camming member 17, while at the right the switch parts are shown as in open position.

The invention in its broader aspects is not 20 limited to the specific mechanisms shown and described but departures may be made therefrom within the scope of the accompanying claims without departing from the principles of the invention and without sacrificing its chief advantages.

What I claim is:—

1. A switching device including in combination 25 a plurality of switches arranged in arcuate relation, each switch including a pair of contacts, one movable and one stationary, said movable con-

tact being mounted on a pivoted arm actuated by snap mechanism, a cam rotatably mounted to move in a path concentric with the switches for selectively actuating the snap mechanism in one direction, a plurality of interconnected springs interconnecting said snap mechanism for actuating the snap mechanism in the other direction and a cylindrical cup concentric with the cam on which the stationary contacts are mounted and by which they are interconnected. 10

2. A switch comprising a plurality of pairs of contacts arranged in arcuate form about an axis, one contact of each pair being mounted on an arcuate base, comprising a curved metallic member serving as a common mounting means for 15 said contacts, a pivoted arm and a snap mechanism for each pair the opposite contact of each pair being supported on the pivoted arm actuated by the snap mechanism, said snap mechanism being adapted to be actuated in one direction by a cam rotatably mounted about said axis, and additional radially disposed springs adapted to actuate the snap mechanism in the opposite direction upon disengagement of said cam from 20 said snap mechanism, said curved metallic member being cup-shaped and a single terminal arranged at one portion of said cup, whereby the same establishes a circuit to all of the contacts 25 arranged on said metallic member and further serves as a securing means for said member. 30
